UNITED STATES PATENT OFFICE.

CHARLES E. HEYER, OF CHICAGO, ILLINOIS, ASSIGNOR TO BARNHART BROS. & SPINDLER, OF SAME PLACE.

DESIGN FOR TYPE.

SPECIFICATION forming part of Design No. 18,250, dated April 10, 1888.

Application filed January 11, 1888. Serial No. 260,451. Term of patent 14 years.

To all whom it may concern:

Be it known that I, CHARLES E. HEYER, a citizen of the United States, residing at Chicago, county of Cook, and State of Illinois, have invented and produced a new and original Design for a Font of Printing-Type, of which the following is a specification, reference being had to the accompanying typographic impressions, which are exact representations of said design.

The character of this design is a sharply-angled slightly-condensed script, comprising capitals, small letters, characters, and points. Its marked peculiarities are that the capitals have fine upstrokes, and downstrokes which are long tapers forming heavy shade-lines, terminating abruptly at the larger ends, that whenever these two kinds of lines meet—the light and shade lines—a sharp angle is formed. The small letters are similar, in that

the upstrokes are light and the downstrokes heavy shade-lines, and that angles are formed where the two meet; but the downstroke shade-lines are of uniform width throughout and not tapers, except that in the letters where a loop ordinarily occurs, instead of the loop, the line is slightly thickened at its end.

I claim—

The design for a font of sharply-angled script printing-type herein shown and described, comprising capitals, characters, and points, having capitals whose stems are tapers finished at their heavier ends by horizontal strokes extending to the left, and small letters abruptly thickened where a loop would ordinarily occur, substantially as described.

CHARLES E. HEYER.
